UNITED STATES PATENT OFFICE

ANTHONY GERSTENKORN, OF BROOKLYN, NEW YORK

SPIKE-SHAFT ROLLED-BEEF MACHINE

Application filed June 9, 1928. Serial No. 284,218.

This invention relates to mechanism for tudging groove to receive a tongue projecting from the cord carrying block body to maintain the same in fixed lateral relation therewith.

A still further feature of construction being present in a plunger comprising a head having spaced nut extensions to engage the threads of a feed worm, the space between said extensions forming an opening through which the binding cord passes on and over the said worm shaft to drive the same, the shank of the said head being extended upwardly through a spring chamber and having an orifice at its upper end to receive a 55
slidable catch adapted to rest upon a shoulder to maintain the said nut extensions free of the worm threads when the cord block is 60
moved back to the starting point.

10 The object of the present invention is to provide improved devices whereby the leading end of the meat may be quickly anchored or fixed to its supporting means for rolling it therearound and quickly removed therefrom when the roll is formed.

15 Another object of the invention is present in improved means for tying or binding the finished beef roll tightly so that it cannot unwind or loosen up in handling.

20 Features of the construction comprise a winding and supporting shaft having short longitudinal movement in opposite sockets and a spring to urge said shaft into locked position into one of the said sockets. The 25 shaft also having pivoted spring raised spikes and longitudinal grooves into which selected spikes may be folded and held out of operative position by devices encircling said shaft, which shaft has also a universal joint to permit raising one end thereof to withdraw a 30 finished roll of meat therefrom.

Further features include means for permitting the anchoring spikes a pivotal swinging movement in one direction only, the direction toward the free end of said shaft, so 35 that when a meat roll is properly prepared sewed and cord bound, it may be drawn outwardly or longitudinally to free it from its supporting shaft as will be readily understood.

A further important feature of the invention is prominently present in a cord tensioning and guiding block device for high tensionally binding, by a single cord, the completed compressed beef roll for the purpose of 45 producing a desirable commercial package for application thereto, of a determined curing medium, such as smoke.

Another feature of construction present 50 is in the provision of a shaft having a longi-

100
Briefly, the invention embodies, a rotatable shaft having hinged spring pressed spiked devices, the ends of said shaft being received in opposite sockets, one socket having a universal joint and an enclosed spring to urge the shaft in one direction; a worm shaft and a guide shaft, a cord feed and tensioning block having means for operatively engaging the worm threads to feed the same, the cord being threaded through said block, thence on and over the said worm, the tensional contact with said worm being sufficient to turn the same and to feed said block therealong.

I clearly illustrate my invention in the accompanying drawings, which form a part of this specification and in which similar reference characters are employed to designate 85 corresponding parts throughout the several views, in which:

Fig. 1 is a front view of my improved meat roll making machine, parts being in section to more clearly disclose the construction.

Fig. 2 is a vertical cross-section of the machine, the section being taken about on the irregular dotted line 2-2 of Fig. 1 and showing also a beef roll at the beginning of the stitching operation, but also indicating 95 in a somewhat imaginary manner the binding cord which will be in reality placed therearound subsequently.

Fig. 3 is an enlarged composite sectional elevational view, showing the approximate 100

relative arrangement and construction of devices employed for tensioning a cord for tightly binding a beef roll.

Fig. 4 is a fragmentary detail elevation of a device shown in Fig. 3 with parts thereof in a different position.

Fig. 5 is a fragmentary detail of a beef roll winding and supporting shaft showing the operative and inoperative positions of hinged spikes employed.

10 Fig. 6 is a detail elevation of a spring pressed nut adapted to engage the feeding worm and carried by the said cord carrying trolley or block.

15 Fig. 7 shows a beef roll made and finished by the machine forming the subject matter of this application.

20 Referring to the drawings in detail, I provide a frame 10 of any desired form to properly support the parts and, as here shown, it may comprise a table 11, a plate 12, top and bottom bars 13 and 14, and bearings in pairs, as at 15 and 16.

25 The plate 12, is preferably mounted under the table 11, in suitable brackets 17 and as herein shown is formed with spaced cross bars 18, and downward directed tubular guides 19 in which guide rods 20 operate to support a bar 21, which rests on end springs 22 arranged on the guide rods 20, and on a heavier central spring 23, encircling a plunger rod 24, carrying a foot pedal 25, at its bottom.

30 Curved basket or cradle bars 26, are fixed to the bar 21 near its ends, and are connected at their ends by side bars 27, having perforated ears 28, from which spaced looped chains 29 are suspended to form a basket or cradle 30 for the purpose of packing the meat as the roll progresses.

40 Mounted in the bearings 15 at the opposite sides of the machine frame 10 are a fixed socket 31, and a shaft 32 driven by sprockets and chain as at 33, by a motor 34, or other source of power.

45 The shaft 32 is connected to a short tube or socket 35 by a universal joint 36, and mounted to rotate with the said tube is a beef rolling shaft 37, which has a cross pin 38 extending into opposite slots 39 the end of said shaft being outwardly urged by a backing spring 40, thus permitting inward sliding movement of said shaft to release its free end from the socket 31 when a beef roll is to be withdrawn or removed therefrom, by elevating that end 50 from the universal joint 36.

55 The beef rolling and supporting shaft 37 is formed along its length with grooves or channels 41 in which a number of spikes 42 are pivoted as at 43; these spikes each have a shoulder 44 (Fig. 5) against which a flat spring 45 bears, to urge and yieldingly maintain said spikes in a vertical or outstanding position with one side bearing against one end of its channel, so that the leading edge of 60 beef to be rolled may be pressed down over

them and be carried around said shaft in its rotation.

65 Rings 46, are slidably mounted on the shaft 37 which are employed to hold unused spikes in their respective channels as shown in Fig. 5. 70

75 Mounted anti-frictionally in the bearings 16 is a horizontally arranged worm or screw shaft 47 and just above in the frame 10 is arranged a parallel fixed shaft 48, provided with a longitudinal groove 49 (Figs. 3 and 4) 75 adapted to receive a tongue 50 projecting into the bore 51, from a cord tensioning block or trolley 52 which is held in constant angular relation with the worm shaft 47 and the beef rolling shaft 37 by the tongue and groove 80 interlocking means just described. Circular ribs 48^a may be provided on the end surfaces of the block 52 around the shaft 48 to increase the bearing length thereof and to provide finished limiting surfaces for the block. 85

90 When a beef roll has been rolled on the shaft 37 and compacted thereon by high tensile pressure exerted by the chains 29 of the basket or cradle 30 by reason of the expansive force of the springs 22-22 and 23, it is then necessary to tie the roll tightly and in practice I have found a spirally wound cord effective for that purpose, but it must be under high tension.

95 Satisfactory results have been attained by employing a strong cord shown at 53, which is first threaded through one or more slots in a tensioning plate 54, thence several times around a grooved pulley 55 mounted in a swivelled hanger 56 thence partially around 100 and under a tensioning shoe 57, backed by a spring 58, which is adjusted by a thumb screw 59 in threaded engagement with a housing 60, extending from the cord tensioning block 52. 105

110 The binding cord 53, after passing under the spring pressed shoe 57, is then passed several times around another grooved pulley 61 mounted between perforated ears 62, on the block 52, and from thence through eyes 115 63, also on said block. The cord is now threaded backwardly through a space 64 (Fig. 6) provided in the head 65 of a feed nut 66, around and in high tensile contact with the feed worm and thence around the meat 115 roll 67 to which the binding cord had previously been tied.

120 The high tensile engagement of the cord 53 with the feed worm 47 tends to turn it and feed the cord tensioning block to the left in Fig. 1.

125 To release the said nut from the worm so that the said block can be moved to the right to start another binding operation, I provide the feed nut with a shank 68, which extends through a spring 69 bearing in the nut head 65, and through a bore 70, the projecting end thereof having a cross opening 71 to receive a 130 slideable catch 72 formed with a finger portion 73 by which the said shank may be drawn

upwardly against the action of the spring 69 to permit said catch to ride onto a shoulder 74, thus the nut 66 is held elevated free of the worm threads until the catch is withdrawn from said shoulder when the nut will again be forced into engagement with said worm for another feeding operation.

Before the binding process is started it is desirable to make a few cross stitches across the tail end of the beef and for this purpose 10 I may employ a hand needle 75, to draw a cord 76 from its roll 76' through the meat after which it may be tied as desired.

While the stitching and tying operations 15 are performed and also when a new piece of beef is being spiked in place, the bar 21, supporting the basket or cradle 30 may be held in the lowered position by a latch 77 of the usual construction as will be understood.

20 Obviously the constructions hereinbefore described admit of further modifications without departing from the spirit and scope of my invention, wherefore I desire to have it understood that I do not limit myself to the 25 precise details shown and described.

What I claim as new, is:

1. In a machine of the class described, a shaft having recesses therein, a spike pivoted in each recess and adapted to be folded into 30 said recess, a flat spring in said recess and a shoulder on said spike engaged by the end of said flat spring and normally being urged by the same into an upstanding position, the other side of said spike then engaging an adjacent wall of the recess and so being prevented from rocking beyond its up-standing 35 position.

2. In a machine of the class described, a shaft having recesses therein, a spike pivoted 40 in each recess and adapted to be folded into said recess, a flat spring in said recess and a shoulder on said spike engaged by the end of said flat spring and normally being urged by the same into an up-standing position, the 45 other side of said spike then engaging an adjacent wall of the recess and so being prevented from rocking beyond its up-standing position, and a sliding ring on said shaft for said spike to keep the same folded down in 50 said recess when so desired.

3. In a device of the class described, a shaft; a bearing to receive one end of said shaft in an unlimitedly slidable manner; a tube slidably receiving the other end of said shaft and 55 being rotatable therewith; a spring in said tube back of said shaft normally urging said shaft in an outward direction and means to limit the outward sliding of said shaft and preventing the release of its end from the tube, said shaft being adapted to be pushed into said tube against the action of said spring to such an extent as to free its other end from said bearing; a rotatable pin journaled adjacent to and aligned with said tube; a uni-

versal joint connecting said tube to said pin, and means to rotate said pin.

Signed at New York, in the county of New York, and State of New York, this 1st day of June, A. D. 1928.

ANTHONY GERSTENKORN.
